UNITED STATES PATENT OFFICE

ROBERT M. JONES, OF CHICAGO, ILLINOIS, ASSIGNOR TO CRANE CO., OF CHICAGO, ILLINOIS, A CORPORATION OF ILLINOIS

VALVE WRENCH

Application filed August 2, 1930. Serial No. 472,567.

This invention relates to a tool for assembling and dissembling valve elements and more particularly to a wrench for removing body seat rings as applied to gate valves.

5 Heretofore it has been necessary to remove a gate valve, particularly those of larger sizes, from a pipe line when it is desired to replace the seating rings therein. After removal of the valve from the line the rings 11 have been removed by spud wrenches inserted through the inlet or outlet of a valve. In the absence of a spud wrench recourse has frequently been had to a hammer and punch or other similar device for unscrewing the 15 valve seat rings. This latter method is of course very objectionable since it is extremely detrimental to the valve seat rings.

In many instances however it is very inconvenient if not impossible to remove the valve 20 from service. It is the purpose of this invention therefore to provide a wrench by means of which valve seat rings may be removed and replaced in valve bodies without removing the valve from service. Accordingly a 25 wrench is provided which has a head insertable through the body of the valve and which engages the valve seat ring. The wrench is provided with a handle which extends exteriorly of the valve body and by means of which 30 the head portion may be rotated to unscrew the valve seat ring.

A better understanding of this invention will be had from the following description given in connection with the drawing, in 35 which:

Fig. 1 is a section taken through the center of a typical valve showing a wrench constructed in accordance with this invention applied to a valve seat ring.

40 Fig. 2 is an end elevation of a wrench constructed in accordance with this invention.

Fig. 3 is a side elevation of the wrench shown in Figs. 1 and 2 illustrating the handle applied to the head.

45 Fig. 4 is a transverse section taken through the center of the head portion of a modified form of wrench, and

Fig. 5 is an end elevation of the wrench head illustrated in Fig. 4.

50 Referring to the drawing and more par-

ticularly to Figs. 1 to 3 inclusive, it will be seen that the complete wrench comprises a circular disc-head 1 and a handle 2, the head being of proper diameter to fit within the seating ring of the valve for which it is 55 designed.

In the illustrated embodiment of this invention the seating rings 3 of the valve are provided with lugs 4 projecting from the inner annular surface of the ring. This construction is customary in seating rings. Accordingly the head or disc of the wrench is provided around its periphery with notches 6, equal in number to the lugs 4 and of sufficient size to receive the latter. Upon one face the disc is provided with a laterally extending flange 7 which may be faced with a gasket 8. The flange 7 prevents the disc from sliding through the valve seat and the gasket 8 therein prevents the face of the seating ring 70 from being marred.

The head is also provided with a plug 9 extending laterally from the center of one face thereof and over which a handle may be placed as will be explained hereafter. The same face of a disc is also provided with a plurality of apertures 11 which may be engaged by a portion of the handle of the tool.

The handle comprises a substantially straight bar 2 provided with an aperture 12 80 upon one end thereof of sufficient diameter to encircle plug 9. Adjacent the apertured end of the handle and so positioned with respect thereto as to enter apertures 11 is a post 13. It can be seen therefore that when the handle is placed over plug 9, post 13 may be engaged in any one of the series of apertures 11 to rotate the disc 1 and thereby unscrew the seating ring 1. The apertures 11 are placed sufficiently close together that the handle 85 may be engaged therein upon a limited throw of the handle, the throw being governed by the size of the opening through the valve body.

In the modification illustrated in Figs. 4 and 5, there is shown a double or reversible tool adapted to be used for removing valve seating rings formed with either recesses or lugs upon their inner peripheries. The head 95 comprises a disc 16 which is provided with a 100

pair of plugs 17 one extending from each face of the disc. Each face of the disc is also provided with a series of apertures 18. The disc is provided with a centrally disposed flange 19 projecting outwardly from the center of the peripheral edge thereof each side of the flange being faced with a gasket 21. The peripheral edge lying upon one side of flange 19 is provided with a series of recesses 22, whereas the peripheral edge upon the other side of the flange is formed with a series of projections 23, the projections 23 and recesses 22 are equal to the number of recesses or projections formed in the valve 15 seating rings.

It follows from the above that the head illustrated in Figs. 4 and 5 may be used with a handle as previously described to remove the valve seating rings having either recesses 20 or lugs formed upon their inner peripheral surface by merely using the proper side of the head.

From the foregoing description it can be seen that a valve wrench has been provided 25 which will permit the removal and insertion of body rings without the necessity of removal of the valve from service. The disc being of proper size to substantially fit within the seating ring of the particular size 30 valve for which the tool is designed and the handle being of thin proportions, the tool may be used in bodies having a narrow body gauge and even in bodies having oval necks 35 as well as round necks. The tool is very simple to make and cheap to manufacture.

It is obvious that slight changes may be made in the details of design without departing from the spirit and scope of this invention as defined in the claims appended 40 hereto.

I claim:

1. A valve wrench comprising a disc-like head of suitable diameter to be received within a valve seat ring when in position in a 45 valve, said disc having a laterally projecting flange arranged to abut the face of said ring when the head is inserted therein, a protective covering on said flange, means on said disc for engaging the inner surface of said ring, 50 a handle for said head and means for locking said handle to said head in any one of a plurality of positions.

2. A valve wrench adapted to be inserted in the valve bonnet opening of a valve to 55 engage the seat ring therein comprising a single disc-like head having a portion of suitable diameter to be snugly received within a valve seat ring when in position in a valve, said disc having a flange projecting laterally 60 from substantially the center of its peripheral edge, the edge upon one side of said flange being provided with a series of projections extending outwardly therefrom and the edge upon the other side of said flange being 65 provided with a series of recesses, a handle

for said head, and means for locking said handle to either side of said head in any one of a plurality of positions.

In witness of the foregoing I affix my signature.

ROBERT M. JONES.
